CLAIM

I claim the ornamental design for a protective helmet, as shown and described.

DESCRIPTION

FIG. 1[.] is [an upper] a top perspective view of [the] a first embodiment of a protective helmet showing my new design; FIG. 2[.] is a [lower] bottom perspective view thereof; FIG. 3[.] is a front elevation view thereof; FIG. 4[.] is a rear elevation view thereof; FIG. 5[.] is a [right] left side elevation view thereof; FIG. 6[.] is a [left] right side elevation view thereof; FIG. 7[.] is a top plan view thereof; [and.] FIG. 8 is a bottom plan view thereof[.].
FIG. 9 is a top perspective view of a second embodiment of a protective helmet showing my new design; FIG. 10 is a bottom perspective view thereof; FIG. 11 is a front elevation view thereof; FIG. 12 is a rear elevation view thereof; FIG. 13 is a left side elevation view thereof; FIG. 14 is a right side elevation view thereof; FIG. 15 is a top plan view thereof; and, FIG. 16 is a bottom plan view thereof.

The broken lines shown in the drawings illustrate portions of the protective helmet that form no part of the claimed design.

1 Claim, 16 Drawing Sheets

Matter enclosed in heavy brackets [ ] appears in the original patent but forms no part of this reissue; matter printed in italics indicates the additions made by reissue.
